UNITED STATES PATENT OFFICE.

CHARLES O. HUCKABAY, OF WILLOW, OKLAHOMA.

TOBACCO-PIPE.

1,070,895.

Specification of Letters Patent.

Patented Aug. 19, 1913.

Application filed May 9, 1911, Serial No. 625,968. Renewed February 7, 1913. Serial No. 746,924.

To all whom it may concern:

Be it known that I, CHARLES O. HUCKABAY, a citizen of the United States, residing at Willow, in the county of Greer and State 5 of Oklahoma, have invented new and useful Improvements in Tobacco-Pipes, of which the following is a specification.

This invention relates to improvements in tobacco pipes, and the object of the invention is to provide a pipe for smokers' use 10 wherein the smoke from the tobacco may be drawn into the mouth of the smoker in a filtered and cool condition.

With the above, and other objects in view, 15 which will appear as the nature of the invention progresses, the improvement resides in the novel construction and arrangement of parts hereinafter fully described and claimed.

20 In the accompanying drawings there has been illustrated a simple and preferred embodiment of the improvement, and in which drawings, Figure 1 is a vertical longitudinal sectional view of a pipe constructed in accordance with the present invention. Fig. 2 25 is a perspective view of the non-heat conducting member employed in connection with the pipe and the ring or casing therefor.

30 In the accompanying drawings, the numeral 1 designates the bowl of the pipe. This bowl has integrally formed thereon and adjacent the lower edge thereof a stem section 2.

35 The numeral 3 designates a reticulated floor for the pipe bowl. This floor is positioned a suitable distance above the smoke outlet 4 provided by the stem 2. Arranged directly below the reticulated floor 3 is a 40 ring member 5, the same being doubled upon itself to form an annular pocket within which is positioned a non-heat conducting member such as a sheet of asbestos, mineral wool, or the like, and designated by the numeral 6. The non-heat conducting element, 45

it is to be understood, is sufficiently fibrous to allow for the free drawing of the pipe by the smoker.

The numeral 7 designates a filtering member comprising a sponge or the like, and 50 which is positioned below the non-heat conducting member 6.

The bore of the pipe extends entirely through the bowl thereof, and the lower extremity of the bore is closed through the 55 medium of a removable stopper 8, the latter being constructed of cork or any other desired material.

From the above description, taken in connection with the accompanying drawings, 60 the simplicity of the device, as well as the advantages thereof, will, it is thought, be apparent to those skilled in the art to which such inventions appertain.

Having thus fully described the said invention, what I claim is:

The herein described construction of pipes comprising a bowl member having a continuous bore and a pipe stem provided with an opening which intersects the said bore, a 70 compressible closure frictionally engaging with the lower open portion of the bowl, said closure having its upper face arranged approximately on a line with the lower wall of the opening of the stem, a flanged 75 ring within the bore of the pipe, said ring having a removable porous non-heat conducting disk, the space between the ring and the closure adapted to provide a filtering chamber, a filtering medium within the 80 chamber and a reticulated floor in the bore of the bowl above the ring and the disk carried thereby.

In testimony whereof I affix my signature in presence of two witnesses.

CHARLES O. HUCKABAY.
